UNITED STATES PATENT OFFICE.

WILLIAM W. UREN, OF SAVONA, BRITISH COLUMBIA, CANADA.

CARTRIDGE-HOLDER.

1,073,721.

Specification of Letters Patent.

Patented Sept. 23, 1913.

Application filed January 8, 1913. Serial No. 740,797.

To all whom it may concern:

Be it known that I, WILLIAM W. UREN, citizen of the Dominion of Canada, residing at Savona, in the Province of British Columbia, Canada, have invented a new and useful Cartridge-Holder, of which the following is a specification.

This invention relates to an individual cartridge holder, such as is used on a cartridge belt, bandolier, or vest, and my object has been to provide a simple holder which will positively retain a cartridge within it against accidental removal and yet from which the same may be quickly and simply released and withdrawn, when required, by the finger and thumb of one hand.

The invention is particularly described in the following specification, reference being made to the drawings by which it is accompanied, in which:

Figure 1 shows the cartridge holder in perspective to an enlarged scale. Fig. 2 is a similar view with a cartridge in position, the dot and dash lines indicating the exaggerated movement of the retainer to free the cartridge and the position of that cartridge when released from engagement with the retainer, and Fig. 3 is a back elevation of the cartridge holder.

In these drawings 2 represents the body of the holder which is bent from thin resili- 30 ent sheet metal to embrace about three-quarters of the body of the cartridge 10, the open portion 3 being to the front.

The body 2 is provided with any suitable means for attachment to a belt or bandolier, either by rivets, as at 4, or by clips punched and bent from the blank of the body 2. From the back of this body 2 a tongue portion projects upward, and its width is sheared for a short distance down the body, as at 5. This tongue is bent backward, as at 6, and is recurved inward to form a retaining engagement 7 over the upper side 40 of the rim of the cartridge 10. Thereafter this tongue is produced backward and upward, as at 8, to form a finger engagement by downward pressure on which the retaining member may be sprung back clear of the cartridge rim, as shown by dot and dash lines in Fig. 2.

Where the cartridge is rimless, as for certain magazine arms, the retaining V 7 may be formed to enter and engage the extractor

groove which engagement may also prevent 55 the cartridge from passing down too far into its holder or the latter object may be attained by shaping the body 2 of the holder to fit the shouldered reduction of the cartridge case. 60

In use, the finger is applied as indicated by the arrow 11 and the thumb to the end of the bullet, as indicated by the arrow 9 and pressure so applied will withdraw the V retainer 7 and will simultaneously press 65 the cartridge upward to the position indicated by dot and dash lines in Fig. 2. From this position the cartridge may be readily withdrawn from the body 2 of the holder. 70

With this holder the cartridge is secure against accidental removal as the spring engagement 7 positively holds the rim of the cartridge against the upper edge of the holder so that there is no slackness to allow 75 of end shake, and until effort is applied between the bullet end of the cartridge and the end 8 of the retaining member to bend that member back, this engagement will hold. This releasing pressure cannot be ac- 80 cidentally exerted by flexure of the body, as is the case with many cartridge holders, as the flexure in this case will tend to press the member 7 into closer engagement.

The holder is simple to manufacture be- 85 ing preferably of one piece; is not liable to derangement and is particularly convenient to use.

Having now particularly described my in- 90 vention, I hereby declare that what I claim as new and desire to be protected in by Letters Patent, is:

1. As a cartridge holder, the combination with a member formed to partially encircle the body of the cartridge and having 95 provision for attachment of the same to a belt, of a resilient retaining member integral therewith, said member projecting above the upper end of the encircling portion and formed to project over the rim of 100 the cartridge and produced upward and backward therefrom to form a finger engagement.

2. As a cartridge holder, the combination with a member formed to partially encircle the body of the cartridge and having provision for attachment to a belt or the like, of a resilient retaining member, said retaining 105

member formed to project within the circle of the holding portion and carried backward therefrom to form a finger engagement.

3. As a cartridge holder, the combination 5 with a cartridge holding receptacle having means for attachment to a belt or the like, of a resilient retaining member carried by the cartridge receptacle on the same side as the belt attachment, said retaining member 10 formed to positively engage the upper side of the rim of the cartridge inserted in the

receptacle and produced backward and upward from this engagement to form a release engagement.

In testimony whereof I have signed my 15 name to this specification in the presence of two subscribing witnesses.

WILLIAM W. UREN.
